EDWARD S. BRISTOL, OF PHILADELPHIA, PENNSYLVANIA, ASSIGNEE TO LEEDS & NORTHRUP COMPANY, OF PHILADELPHIA, PENNSYLVANIA, A CORPORATION OF PENNSYLVANIA

CONTROL APPARATUS

Original application filed December 18, 1924, Serial No. 756,856. Divided and this application filed September 21, 1929. Serial No. 394,366.

This invention relates to improvements in control apparatus.

One of the objects of the present invention is to provide improved control apparatus having advantages over the various constructions proposed heretofore as regards simplicity and ruggedness of construction, sensitivity and reliability of operation, and adaptability to different machines, equipment or a device or element to be controlled in accordance with varying conditions.

Other objects and advantages will hereinafter appear.

For the purpose of illustrating the invention, several embodiments thereof are shown in the drawings, wherein

Figure 1 is a diagrammatic view, partly in section, showing the manner in which apparatus constructed in accordance with the present improvements may be embodied in a control system for a steam generator;

Fig. 2 is a diagrammatic view, partly in section, showing a modified construction of apparatus embodying the present improvements;

Fig. 3 is a side elevational view, looking toward the left in Fig. 2; and

Figs. 4, 5, 6 and 7 are diagrammatic views illustrating, respectively, other modified constructions of apparatus embodying the present improvements.

Referring to Fig. 1, B is a steam boiler or generator comprising a drum D in communication with the water tubes T, which latter are disposed in a heating chamber comprising the furnace or fire chamber F from which the hot gases pass around the tubes T and thence outwardly through the stack S provided with the damper d operable by hand or automatically through the pivoted lever a provided with the counterweight b and the actuating or control cord or chain c.

Steam is delivered through the line or conduit C to steam turbines or engines, or other steam-consuming devices. Steam is supplied through the pipe e to the engine or motor f, which drives the stoker g which delivers fuel to the fuel bed h disposed upon the grate i, upwardly through which and the bed h air is supplied at varying rate by the air blower A

driven by any suitable means, as, for example, the electric motor M, which is in turn controlled in response to variations in the pressure of the steam delivered by the generator B.

Connected with the conduit C is the pipe j, through which the steam pressure is applied to the interior of the chamber k closed by the flexible or yielding diaphragm m, upon which is carried the knife edge or pivot n, upon which rests the lever or beam o provided with the pivot or knife edge p engaging the under side of the abutment q. Movable along the lever o is the member r, which may be secured thereto in any of its adjusted positions by the set screw s. Pivoted to the fixed member t at u is the lever v, along which is movable the member w, which may be secured in any of its adjusted positions by the set screw x. The link y is pivoted at its opposite ends to the members r and w, whereby movements or deflections of the lever o are imparted to the lever v. By adjusting the members r and w to different positions along their respective levers o and v, the ratio of angular movements of the levers o and v is variable or adjustable for the purpose of varying with respect to the pressure change effective upon the diaphragm m the magnitude of the resultant control effect, as, for example, control of the speed of the motor M and therefore control of the rate of combustion in the generator B.

Opposing the pressure applied to the under side of the lever o by the diaphragm m is the weight z, hung by the knife edge a1 upon the lever o. For operating cumulatively with the weight z upon the lever o there may be utilized the spring b1, connected at its one end to the lever o and at its opposite end to the member t, the tension of the spring being adjustable by the screw c1. The effect of the spring b1, if and when employed, is to reduce the extent of motion or deflection of the lever o for a given change in steam pressure, with the result that larger pressure changes are required to produce a given magnitude of control effect.

Hung upon the lever o, and operating thereon cumulatively with either or both the

weight z and spring b_1 , is the tank or chamber d_1 connected by the flexible tube e_1 through the throttling valve f_1 with the stationary or fixed chamber g_1 having the vent h_1 to atmosphere. In the chambers g_1 and d_1 is contained liquid i_1 , which may be of any suitable character, as water, oil, etc. The spaces in the chambers d_1 and g_1 above the liquid therein are connected through the flexible tube j_1 .

Carried by and insulated from the lever v is the movable contact k_1 of a rheostat comprising the resistance m_1 , the amount of which in circuit is increased by downward movement of the contact k_1 . The direct current shunt motor M receives its current from the supply conductors n_1 and o_1 , across which are connected the motor armature and motor field, the adjustable resistance m_1 being connected in series with the motor field through the conductors p_1 , q_1 , whereby the field of the motor M is weakened or strengthened as the contact k_1 descends or ascends, effecting corresponding increase or decrease of speed 25 of the motor M , and therefore of the blower A , and thereby increasing or decreasing the rate of combustion of fuel in the generator B .

While the weight z , spring b_1 and chamber d_1 are shown as applied directly to the lever o , it will be understood that any one or more of them may be applied to the lever v to apply thereto a downward force to the left of its pivot u . And it will be understood that these members, or equivalents of them, may 35 be similarly applied to the secondary levers corresponding with lever v of any of the other arrangements hereinafter described.

The operation of a system of the character illustrated in Fig. 1 is as follows:

40 Assuming that the standard or reference pressure of the steam delivered through the conduit C shall be, for example, 250 pounds per square inch, the normal control, that is, the control effected by the lever o under the 45 control of the diaphragm m and either or both the weight z and spring b_1 , but without change in the chamber d_1 , or without change in the amount of liquid therein, will, for changes of load within suitable limits, maintain the 50 boiler pressure within the range of, for example, 245 to 255 pounds per square inch.

Upon occurrence of load or increase of load upon the generator B , the pressure will fall, for example, to 247 pounds. There will be 55 a corresponding reduction in pressure in the chamber k , and the diaphragm m will yield downwardly to corresponding extent because of the now preponderance of control upon the lever o by either or both the weight z and spring b_1 . In consequence, the contact k_1 descends, cutting resistance into the field of the motor M , and thereby correspondingly increasing the speed of the blower A and the rate of combustion. The speed of the blower A effected by the aforesaid descent of con-

tact k_1 may be such as to increase the rate of combustion to such magnitude that during the persistence of the same load which caused the descent of the diaphragm m the steam pressure of the generator will be maintained 70 at the aforesaid magnitude of 247 pounds. Such normal control may effect, as stated, the maintenance of the steam pressure during persistence of load at the subnormal pressure of, say, 247 pounds, or the adjustments 75 or proportions may be such that the rate of combustion will permit the steam pressure to further slowly or slightly decrease or slowly or slightly increase with respect to 247 pounds. When equilibrium is attained, with 80 the speed of blower A just sufficient to maintain combustion at the rate required by the increased load, the steam pressure will become stabilized at the value necessary to hold contact k_1 at a position corresponding with 85 the increased speed of motor M .

The action of the chamber d_1 , however, is to vary the normal control by superimposing thereon a compounding control, effective immediately the lever o deflects. The superposed or auxiliary control is direct, in the sense that it is dependent directly upon the deflection of the lever o , and not indirectly upon any force due to or representative of a change effected through the normal control 90 apparatus. More specifically in the example illustrated, the superposed or the compound control is effected by flow of liquid through the throttle valve f_1 and tube e_1 into the chamber d_1 , thereby applying greater weight 95 to the lever o . This bias or force is therefore directly applied, and directly and immediately in response to deflection of the lever o , and in this instance greater as the deflection of lever o is greater; it is not due 100 indirectly to the effect of the control, as of the blower A or any other steam-pressure-changing means, as effected in response to deflection of the lever o . When the lever arm o finally attains equilibrium after a change of load, 110 the superposed control has acted to change the loading weight on lever o in a predetermined manner, so that the steam pressure attains a predetermined value for each position 115 of the regulating mechanism.

Because of the increased weight applied to the lever o by the liquid passing from chamber g_1 into the chamber d_1 , the control is compounded in the sense that notwithstanding the persistence of the load upon the generator B which caused the fall in steam pressure, the speed of the blower will be such as to effect a rate of combustion more than sufficient to maintain the steam pressure at 247 pounds, and will cause it to rise or return to 250 pounds; or the control may be over-compounded and cause a rise in the steam pressure during the persistence of the load to a value even higher than 250 pounds. The 1 nature of the compounding action is prede-

terminated as desired by suitably fixing the size and shape of the chambers $d1$ and $g1$.

The effect of the superposed or compounding control is, therefore, to cause an amplification or exaggeration of the normal control to effect the application of an agent, such as an agent affecting the rate of combustion in the example illustrated, or any other condition or factor upon whose magnitude depends the magnitude of the steam pressure.

The throttle valve $f1$ is provided to prolong or retard the flow of liquid from chamber $g1$ into chamber $d1$ upon deflection of the lever o ; or to delay or retard the flow in reverse direction from chamber $d1$ into chamber $g1$ in event of steam pressures above the standard or reference pressure, or within the upper part or beyond the upper part of the range of pressures within which the normal control is by itself effective. By preference, the valve $f1$ is so nearly closed as to introduce a considerable time factor as regards the application of the superposed or auxiliary control to prolong the desired steam pressure change throughout a period of, for example, ten to fifteen minutes, more or less.

While for purposes of illustration I have described the control of the rate of application of air to a combustion chamber of a steam generator, it will readily be understood by those skilled in the art that the control effected by deflection of the lever o may be of any other combustion factor, as rate of delivery of fuel, position of damper d , or any two or more of them, or of any other agency, in systems other than those for the generation of steam, whose magnitude, rate of application, or position may determine or affect the pressure to be regulated. Similarly, in the arrangements of Figs. 2 to 7 inclusive, the control mechanisms there disclosed may be used in a system such as indicated in Fig. 1, or in a system of any other character above referred to for controlling the magnitude, rate of application or position of a control agent.

Referring to Figs. 2 and 3, there is illustrated an arrangement in which along the secondary lever v is adjustable the member $r1$, to which there is pivoted the link $s1$ pivoted at its upper end to the member $t1$ adjustable along the member $u1$ carried upon the piston rod $v1$, upon which is secured the piston $w1$ movable in the cylinder $x1$. To the rod $v1$ is connected also the chain c , which, as indicated in Fig. 1, is utilizable for varying the position of the damper d to thereby vary the rate of combustion of the generator B, as when natural draft is used, or as when forced draft is supplied so as to maintain a desired pressure in the furnace F, as will be understood by one familiar with the art. The lower and upper ends of the cylinder $x1$ are connected through the pas-

sages $y1$ and $z1$, respectively, with the upper and lower ports $a2$ and $b2$ of the pilot valve structure comprising the chamber $c2$, in which is movable with respect to the ports $a2$ and $b2$ the slide valve $d2$ operated by the rod $e2$ pivoted to the lever v at $f2$. Fluid under pressure, as steam, air, water, etc., is delivered through the pipe $g2$, and directed according to the position of the valve $d2$ into the cylinder $x1$ on one side or the other of piston $w1$, the fluid being exhausted through the exhaust or discharge outlet $h2$.

By the adjustment of the members $r1$ and $t1$ along the lever v and member $u1$, respectively, the distance between the pivot $f2$ and the pivotal mounting of the lever v upon the member $t1$ through the link $s1$ is varied to procure any suitable ratio of movement of the slide valve $d2$, whose movement is further affected by the ratio of movements of the levers o and v as determined by the positions of the members r and w upon the levers o and v , respectively.

In general, the operation is similar to that described in connection with Fig. 1, in that the flow of liquid from chamber $g1$ into chamber $d1$ upon downward deflection of the lever o effects a superposed or amplified control causing the piston $w1$ to move in such a direction and to such extent as to move the damper d in such direction and to such extent as to effect a rate of combustion which may be such either as to maintain the pressure corresponding with the increased load, or as to cause such pressure to rise and return to or beyond the standard or reference pressure.

The piston $w1$ by its motion reacts through the lever v upon the valve $d2$ to return it to or toward its port-closing position. In the example illustrated, a downward deflection of the lever o causes upward movement of the piston $w1$ and of chain c , and reacts upon the valve $d2$ to return it upwardly toward or to port-losing position.

With structure of this type there is a definite position of the piston $w1$ corresponding to any position of the arm o within the working range. The use of the piston $w1$ and its adjuncts of the character described may, as indicated, be utilized in lieu of the motor M and its control, of Fig. 1, or of Figs. 4 to 7.

Referring to Fig. 4, there is shown control apparatus utilizable in systems of the character described in connection with Fig. 1, and in which again there is provided a superposed or auxiliary control directly responsive to change in the pressure to be controlled.

There is applied to the system which deflects in response to pressure changes a superposed or auxiliary control force by the spring $i2$ connected to the deflecting system to operate cumulatively thereon with either or both the weight z and the spring $b1$; the spring $i2$ is connected also to the cord or chain $j2$ pass-

- ing over suitable idler rollers and connected to the nut k_2 through which is threaded the shaft m_2 , upon which is secured the worm gear n_2 driven by the worm o_2 secured upon the shaft of the reversible electric motor M_1 receiving current from the supply conductors p_2 and q_2 , in which latter is disposed the speed-controlling resistance r_2 and which is connected to the contact s_2 carried by and 10 insulated from the deflecting member o . Carried by the nut k_2 is the rod t_2 , which carries the block of insulating material u_2 , upon which are secured the flexible or yielding conducting strips v_2 and w_2 carrying, respectively, the adjustable contacts x_2 and y_2 connected, respectively, in the leads of the different field windings of the motor M_1 , whereby when the contact s_2 is in engagement with contact x_2 the motor M rotates in one direction, and 15 in the opposite direction when the contact s_2 engages the contact y_2 , in which latter case the nut k_2 is moved downwardly to increase the tension upon the spring i_2 and thereby increase the force acting downwardly upon the lever o . The gear ratio as between the shaft 20 of the motor M_1 and the nut k_2 , and the magnitude of the resistance r_2 , are such that the nut k_2 moves slowly, thereby introducing a time factor or lag as regards application of 25 the auxiliary or superposed control, as effected in the arrangement of Fig. 1 by the throttle valve f_1 .
- As the nut k_2 descends, the increased force applied downwardly upon the lever o increases the loading force when the pressure falls, and, vice versa, decreases the loading force when the pressure rises, in which latter case the nut k_2 ascends because of engagement 30 of the contact s_2 with contact x_2 .
- 35 The contacts x_2 and y_2 are yieldingly mounted, so that notwithstanding relatively great displacements of the lever o there shall not be offered thereto appreciable opposition.
- 40 Obviously, the contact s_2 may be carried upon the lever v , or upon any other member moving in unison with the diaphragm m .
- 45 In Fig. 5 there is shown a generally similar arrangement, but in this case the block u_2 remains stationary and the nut k_2 carries a pivot u for the lever v .
- 50 Upon drop in pressure, the downward deflection of the lever o , which tends to balance in a horizontal position when equilibrium is attained, closes circuit at the contacts s_2 and y_2 , causing the nut k_2 to ascend, causing a drift or shift of the contact k_1 with respect to the fixed resistance m_1 , and having in general the effect of superimposing a direct auxiliary control, of the character effected by 55 passage of fluid from chamber g_1 into chamber d_1 in Fig. 1. The auxiliary control is again effected slowly, as in Fig. 4. When the pressure is returned to standard, lever o rises to a horizontal position, circuit is opened at 60

the contacts s_2 and y_2 , and the superimposed drifting action ceases.

To prevent travel beyond the control range, there are provided in the circuits of the contacts x_2 and y_2 the limit switches z_2 and a_3 , 70 respectively. The limit switches are opened after predetermined extent of movement of the nut k_2 by the member b_3 movable therewith, or may be actuated by contact k_1 , as shown in Fig. 6.

In Fig. 6 there is illustrated a generally equivalent arrangement. A cord c_3 is attached at its ends to the levers o and v and passes over idlers, one of which, d_3 , is carried by the nut k_2 . And applied to the lever 80 v is a weight e_3 , or equivalent. In this case the limit switches z_2 and a_3 are opened at the extremes of travel of contact k_1 , or may be opened after predetermined travel of the nut k_2 , as described in connection with Fig. 5. 35

In this arrangement again there is effected a drifting motion of the contact k_1 in one sense or the other, according to the sense of deflection of the lever o , and this drifting motion, as in Fig. 5, effects a direct and immediately superposed or auxiliary control having the purpose and effects hereinbefore described.

In Fig. 7 there is again shown a generally similar arrangement. In this instance, however, the resistance m_1 is moved by the nut k_2 with respect to the contact k_1 upon deflection of the lever o to effect the direct superposed or auxiliary control.

While but a single steam generator has 100 been described as controlled, it will be understood that any number of them may be simultaneously controlled by one and the same mechanism in response to their common steam pressure. In such case the blower A may 105 supply air for all of the generators of the battery, or each generator may have its own blower A driven by its individual motor M , in which case several rheostats k_1 , m_1 may be operated in unison by the control mechanism, as, for example, by the member o thereof. Or in the case of the arrangement indicated in Figs. 2 and 3, the several stack dampers d of the different generators, or at least different furnaces, may be moved in unison 110 by the piston w_1 .

This application is a division of my co-pending application Serial No. 756,856, filed December 18, 1924.

From the foregoing it will be seen that 115 improved control apparatus has been provided including means, such as the fluid-pressure motor $k-m$ and lever o responsive to variation in conditions to which the apparatus is subjected, such as variation in steam pressure conditions of boiler B in the system shown in Fig. 1, such means being operable to effect controlling action of the apparatus through a control range corresponding to such variation. Further, it will be seen that the 120

apparatus includes means, such as chambers g_1 and d_1 in Figs. 1 and 2 and nut k_2 in Figs. 4 to 7, rendered effective consequent upon operating action of motor $k-m$ and the associated lever o , and being operable upon becoming effective to induce controlling action of the apparatus beyond the control range effected by operating action of the motor and lever o . While the various modifications or arrangements shown and described are presented as practical embodiments of the present invention, it is to be understood that various other changes or modifications, such as in the size, shape or arrangement of the parts, might be made without departing from the spirit of the invention or the scope of the claims.

The invention claimed is:

1. In control apparatus, pressure responsive means including a movable member, a resistance, a contact adjustable along said resistance, structure mechanically connecting said movable member to said adjustable contact for movement thereof at a rate of departure of pressure from a predetermined value; said means, said resistance, said contact and said structure comprising a primary controller immediately and substantially proportionally responsive to pressure changes; and auxiliary control means for gradually applying a control cumulative with and continuing for a substantial period after said primary control comprising a motor and speed-reducing means for slowly effecting relative movement of said contact and said resistance, and switch mechanism operated by said member to control said motor.

2. In control apparatus, a deflecting member responsive to the controlled condition, a resistance, a pivoted contact therefor, a link connecting said member and said contact, structure forming an adjustable fulcrum for said pivoted contact, a motor and speed-reducing means for adjusting said structure, and contact mechanism operable by said member for controlling said motor.

3. In control apparatus, a deflecting member responsive to the controlled condition, a resistance, a contact therefor, structure mechanically connecting said member to said contact, and means operating upon said structure to vary the distance between said member and said contact to effect a compensating control comprising a motor, speed-reducing means interposed between said motor and said structure, and contact mechanism operable by said member for controlling said motor.

4. In control apparatus, a deflecting member responsive to the controlled condition, a resistance, a contact therefor, a flexible member connecting said deflecting member and said contact having a loop, and means for changing the length of said loop to effect an auxiliary control comprising a motor, speed-

reducing means, and contact mechanism operable by said deflecting member for controlling said motor.

5. In combustion control apparatus for vapor generators, means responsive to pressure including a deflecting member, a primary control system for controlling the combustion rate, comprising a resistance and an adjustable contact mechanically connected to said deflecting member for movement in immediate response to pressure changes, and means for effecting a supplemental control of the combustion rate to compensate for the falling characteristic of the system comprising a motor, speed-reducing means, contacts operable by said deflecting member to control said motor, and means mechanically connecting said speed-reducing means to said primary control system gradually to move said contact in the same direction as effected by the primary control but beyond the final position possible by action of said primary control.

6. In control apparatus for vapor generators, a balanced system comprising a weighted lever and a diaphragm subjected to vapor pressure, a resistance, a control movable along said resistance to determine the combustion rate, link structure directly connecting said lever to said contact arm, a spring connected to said lever for opposing movement by said diaphragm, and means for varying gradually the tension of said spring to effect compensated control of combustion comprising a motor, contacts adapted to be operated by said weighted lever and mounted on a movable support, and speed-reducing means interposed between said motor and said spring and between said motor and said contact mounting.

7. In combustion control apparatus for vapor generators, means responsive to the vapor pressure including a deflecting member, a primary control system for controlling the combustion rate, comprising a resistance and an adjustable contact mechanically connected to said deflecting member for varying said resistance in immediate response to pressure change, and means for effecting a supplemental control of the combustion rate to compensate for the falling characteristic of said system comprising a motor, speed-reducing means, contacts operable by said deflecting member to effect a control of said motor, and means mechanically connecting said speed-reducing means to said primary control system gradually to effect further change of resistance in the same sense as effected by the primary control but beyond the final value possible by action of the primary control.

8. In control apparatus, pressure responsive means including a movable member, an adjustable resistance for controlling the magnitude of said pressure, means for promptly

checking change of said pressure from a predetermined value comprising means interconnecting said movable member to said adjustable resistance for variation thereof at substantially the rate of departure of said pressure, and means for gradually restoring the pressure by further and slower variation of said resistance comprising a motor, speed-reducing means interposed between said

10 motor and said adjustable resistance, and mechanism operated by said member to effect a control of said motor.

9. In control apparatus, a deflecting member responsive to the controlled condition, a

15 variable resistance for controlling said condition, means for promptly checking departure of said controlled condition from a predetermined value comprising means interconnecting said movable member to said adjustable resistance to effect variation thereof at sub-

20 stantially the rate of departure of said condition, and means for gradually restoring said condition by further and slower variation of said resistance comprising a spring connected

25 to said member, a motor and speed-reducing means for continuously and gradually changing the tension of said spring in a sense resulting in further movement of said deflecting member always in the same direction as

30 the initial movement of said member in response to departure of the condition, and switching mechanism controlling operation of said motor comprising movable contact structure operated by said deflecting member

35 and cooperating contact structure slowly movable in the path of said first contact structure by said motor and speed-reducing means.

10. In control apparatus for a vapor generator, vapor pressure responsive means

40 including a deflecting member, a combustion control member, structure connecting said deflecting member to said control member for effecting change in the rate of combustion substantially immediately to an extent deter-

45 mined by the extent of departure of the vapor pressure, and means for gradually restoring the vapor pressure comprising a slowly acting motive mechanism for effecting change in the position of said control member, and

50 means engaged by said deflecting member to initiate operation of said motive-mechanism and disengaged from said deflecting member upon restoration of the vapor pressure to stop operation of said motive-mechanism.

55 EDWARD S. BRISTOL.
